Thomas H. D. Motte

United States Patent Office.

THOMAS H. DE MOTTE, OF WOODFORD COUNTY, ILLINOIS.

Letters Patent No. 90,042, dated May 11, 1869.

IMPROVED WASHING-MACHINE.

The Schedule referred to in these Letters Patent and making part of the same.

To all whom it may concern:

Be it known that I, THOMAS H. DE MOTTE, of the county of Woodford, and State of Illinois, have invented a new and useful Machine for Washing Clothes, &c.; and I do hereby declare that the following is a full, clear, and exact description of the construction and operation of the same, reference being had to the annexed drawings, making a part of this specification, and in which like letters refer to like parts.

Figure 1 represents a perspective view.

Figure 2, a longitudinal vertical section.

I construct the main chamber A A of an oblong shape, with parallel vertical sides, the bottom sloping at a small angle toward the reserve-chamber, which occupies one end of the machine.

The side of this chamber B facing the main chamber is perforated, b, and leans at an angle into the latter, but is water and steam-tight elsewhere.

Its juncture with the bottom, or "incline" of the box is covered by the perforated or channelled strip t, which allows of the filtering or passage into the reserve-chamber all sedimentary matter.

A plug, n, on the outside of the latter, is for discharge of waste water, and an upper extension of the outer side of this chamber is intended for the attachment thereto of a clothes-wringer.

The junctures of the sides and bottom of the main chamber are covered by strips of wood, or curved "tramways" for the passage thereon of the friction-rollers of the plunger. These strips are much thicker at the upper end of the box, but descend in a curve to within an inch or less of the bottom at the reserve-chamber. The strips thus described are seen at f f.

The plunger C is a stout block of wood, pierced through its thickness with several holes, but not placed opposite the holes in the reserve-chamber B b.

The upper edge or part of the plunger is bored with sockets along its whole length, p.

The plunger is also provided with friction-rollers s, one at either end of the block, and let into the wood, and running on pins, or iron axles, and bear on the tramway f f.

The face of the plunger is inclined backward, or parallel with the perforated front of the reserve-chamber B, and, of course, occupies the whole width of the box A A.

Its height is not such as to strike the cover k, when drawn to the upper end of the box.

Two bars of iron or wood d d are fastened into the back of the plunger, one on each side, their inclination being upward, and about the same angle of ascent with the bottom of the machine, and passing out through bearings i i in the end of the box, the latter being a portion of the drip-cups set beneath, each bearing to catch water from the bars d d.

The bars terminate in the cross-handle e, and are long enough to work the plunger through the whole length of the box.

The whole machine is steam-tight, as well as water-tight, and is provided with a hinged cover k, united by a hinge m to the cover k, on one side, and having an overlapping tongue, which fits into a similar tongue on the top of the reserve cover g, and is fastened with a button.

A "stay" rod, u, is attached to the part of the box between the drip-cups i i, to hold the handle.

The operation of this machine is obvious. The clothes are introduced between the reserve-chamber B and the plunger C. The latter being forced back and forth, forces the water, or suds through the material in strong currents, forcing, at the same time, surrounding water into the reserve-chamber B, on one side, and into or through the perforations in the plunger C, on the other side, where the water runs back again, on the "incline," to the clothes. The rotating of the clothes is consequent on the inclination of the reserve-chamber and the face of the plunger, the clothes lying against the latter, on compression, and on the withdrawal of the same, have a tendency to fall over in that direction, which is further assisted by the action of the sockets p, in the plunger, by their sucking action, when withdrawn, after pressure on the clothes.

Simultaneous with this operation, the reserve-chamber is filled with water at each pressure of the plunger, and pours out on to the clothes in many streams, increasing the cleansing process, and helping to rotate the clothes, in order to present a new surface to the impact of the plunger and the water-currents. The cover should be tightly closed during washing, to retain all the steam possible.

The soiled water is drawn off through the hole in the reserve-chamber, closed by the plug n.

The rod u is used to keep the plunger back, while putting in the clothes, &c.

Having thus fully described my invention,

What I claim as new, and desire to secure by Letters Patent, is—

In a washing-machine, the plunger C, with sockets, p, perforations, a, reserve-chamber, B, sediment-receiver, t, inclined bottom, D, and tramway, f f, stay-rod, u, drip-cups, i i, handle e, and rods, d d, all constructed, arranged, and combined, substantially in the manner and for the purpose as herein shown and set forth.

THOMAS H. DE MOTTE.
